PLASTIC SHEET MATERIAL

Thomas C. Hendrickson, South River, N.J., assignor to
Colgate-Palmolive Company, New York, N.Y.

Filed June 10, 1974, Ser. No. 477,607

Term of patent 14 years

Int. Cl. D5—06

U.S. Cl. D87—3 G

FIG. 1

FIG. 2

FIG. 1 is a plan view of a plastic sheet material embodying my new design; and

FIG. 2 is a longitudinal view thereof taken along the plane of line 2—2 in FIG. 1.

I claim:

The ornamental design for a plastic sheet material, as shown.
